UNITED STATES PATENT OFFICE.

GEORGE A. WOODMAN, OF CHICAGO, ILLINOIS, ASSIGNOR TO AUGUST J. WEIL, OF NEW YORK, N. Y.

DESIGN FOR A BRASS FOR CAR-AXLE BEARINGS.

SPECIFICATION forming part of Design No. 34,580, dated May 28, 1901.

Application filed April 29, 1901. Serial No. 58,090. Term of patent 14 years.

To all whom it may concern:

Be it known that I, GEORGE A. WOODMAN, a citizen of the United States, residing at Chicago, in the county of Cook and State of Illinois, have invented and produced a new and original Design for a Brass for Car-Axle Bearings, of which the following is a specification, reference being had to the accompanying drawings, forming part thereof, and in which—

Figure 1 is a side view of a brass embodying my original design. Fig. 2 is a top plan view. Fig. 3 is an end view.

The brass A is substantially oblong in shape and provided with upwardly-projecting lugs C at its ends, a central circular portion D, and side lugs B opposite said circular central por-

tion and projecting beyond the plane of the sides, of which they form a part.

The leading feature of the design consists ²⁰ of the side lugs B opposite the central circular portion D, which gives to the brass a characteristic shape and configuration.

What I claim is—

The design for a brass for car-axle bearings, ²⁵ substantially as shown and described.

In testimony whereof I have signed my name to this application, in the presence of two subscribing witnesses, at Chicago, Illinois, this 27th day of April, 1901.

GEORGE A. WOODMAN.
